UNITED STATES PATENT OFFICE.

LOUIS DUSSART, OF KINCAID, ILLINOIS.

BRACE FOR SLIDE-RAILS.

1,333,584.

Specification of Letters Patent.

Patented Mar. 9, 1920.

Application filed November 12, 1919. Serial No. 337,380.

To all whom it may concern:

Be it known that I, LOUIS DUSSART, a citizen of the United States, residing at Kincaid, in the county of Christian and State of Illinois, have invented certain new and useful Improvements in Braces for Slide-Rails, of which the following is a specification, reference being had to the accompanying drawings.

10 This invention relates to slide rail braces for mine railways.

The end portions of the permanent rails of mine tunnel railways are provided with sliding rails which are attached to the inner 15 sides of the rails and are moved along as the mining progresses until it is possible to lay full lengths of permanent rails. In view of the fact that these rails are disposed at the ends of the permanent rails and are intended 20 to be moved at intervals it is not advisable to permanently secure them, and as the mine car is supported by the slide rails there is constant danger of the rails spreading and derailing the car.

25 It is therefore the object of this invention to provide a brace for slide rails of mines which positively prevents spreading of the rails.

Another object is the provision of a brace, 30 the rail engaging members of which are formed in one piece conforming to the contour of the slide rail to prevent disengagement of the brace.

Another object is the provision of a brace 35 of this character, the rail engaging members of which are adjusted simultaneously to brace the rails.

With these and other objects in view the invention consists in the improved construction 40 and arrangement of parts to be herein-after more particularly described, fully claimed and illustrated in the accompanying drawings, in which:—

Figure 1 is a plan view of the brace applied to the slide rails.

45 Fig. 2 is a side elevation of the brace applied.

Referring to the drawings A indicates the permanent end rails of the mine railway and 50 B the slide rails thereof. My improved brace is intended to engage the base flanges of the rails B and consists of a pair of shackles 5, each shackle being constructed to conform to the contour of the base of the rail 55 and is intended to snugly engage the same. The outer side portions 5' of each shackle

converge inwardly to the intermediate portion thereof so as to permit the shackle to be placed closely adjacent the side of the rail so that one converging portion projects into the 60 path of the wheel of the car to serve as a bumper. Extending rearwardly from the shackles, are shanks 6 and 7. The shank 6 is provided with right hand threads while the shank 7 is provided with left hand threads, 65 the shanks being in alinement. A turnbuckle 8 is provided for connecting the shanks 6 and 7 and includes threaded ends 9 and 10, the end 9 being arranged to receive the threaded shank 6 while the end 10 is 70 arranged to receive the threaded shank 7, the ends 9 and 10 being threaded to correspond to the shank disposed therein.

A partition 11 is disposed centrally of the turnbuckle and is arranged to prevent contact of the inwardly moving ends of the shanks 6 and 7, with each other. To further secure the brace against accidental disengagement from the slide rails B, each shackle 5 has connected thereto by means of a chain 80 12, a holding pin 13 adapted to be disposed in openings formed in the slide rails.

In the use of the brace, the shackles are positioned so that they may be easily applied 85 at the ends of the slide rails and moved longitudinally thereof to the desired position, it being impossible for the shackles to disengage themselves from the rails in view of the fact that no part thereof is movable. When the shackles are in this position, upon 90 rotation of the member 8 the shanks 6 and 7 may be adjusted to the extent necessary.

From the foregoing it will be readily seen that this invention provides a novel form of brace for slide rails which is capable of 95 being readily applied and removed, is easily adjusted and positively prevents spreading of the slide rails.

What is claimed is:—

1. A brace for slide rails of a mine railway 100 comprising a pair of shackles adapted to partially surround the slide rails, and means carried by said shackles for adjusting the same with reference to each other and with the rails.

2. A brace for slide rails of a mine railway comprising shackles adapted to encircle the base flange of the slide rail, each shackle including a shank, and means rotatable on said shanks for moving said shackles toward 110 and away from each other.

3. A brace for slide rails of a mine railway

comprising a pair of vertically disposed shackles adapted to snugly engage the base flanges of the slide rails, a threaded shank projecting from each shackle in angular relation thereto, and a threaded rotatable member connecting said shanks to move the same toward or from each other upon rotation of said member.

4. A brace for slide rails of a mine railway comprising shackles adapted to encircle the

base flange of the slide rail, each shackle including a shank, and means rotatable on said shank for moving said shackles toward and away from each other, the outer side of each shackle having faces converging toward and terminating at the side opening therein to provide bumpers. 15

In testimony whereof I hereunto affix my signature.

LOUIS DUSSART.
